UNITED STATES PATENT OFFICE.

ALBERT D. GROVER, OF NEW YORK, N. Y., ASSIGNOR, BY MESNE ASSIGNMENTS, TO
AUTOSALES CORPORATION, A CORPORATION OF NEW YORK.

SLOT-CLOSING MECHANISM FOR COIN-CONTROLLED VENDING-MACHINES.

1,310,826.

Specification of Letters Patent. Patented July 22, 1919.

Original application filed May 11, 1915, Serial No. 27,302. Divided and this application filed October 29, 1915. Serial No. 58,543.

To all whom it may concern:

Be it known that I, ALBERT D. GROVER, a citizen of the United States, and a resident of New York city, in the county of New York and State of New York, have invented certain new and useful Improvements in Slot-Closing Mechanism for Coin-Controlled Vending-Machines, of which the following is a specification.

10 This application is a division of my co-pending application, Serial No. 27,302, filed May 11, 1915. Owing to an official requirement for division, the claims in said co-pending application directed to the slot-closing device of my invention were canceled and are, therefore, presented in the present divisional case.

20 The object of my invention as set forth in this application is the provision of means for automatically closing the coin-entrance slot of the machine when the supply of goods is exhausted. The slot-closing mechanism of my invention is characterized by the fact that it normally forms a yieldable obstruction to an entering coin and is automatically locked against movement into unobstructing position as soon as the magazine is empty.

30 In the preferred form of my invention, my new slot-closing mechanism also constitutes a washer-catching device. That is to say, when a washer or any disk with a central perforation is attempted to be inserted into the machine, the washer is automatically locked against full insertion into the coin-slot, although it may be readily withdrawn. The obstructing member is automatically locked in obstructing position through the medium of a weight which normally rests on the column of goods in the magazine.

40 A preferred form of my invention is shown in the accompanying drawings, in which—

Figure 1, shows the interior mechanism of a vending machine embodying my new slot-closing device, the view being taken approximately on line 1—1 of Fig. 2.

50 Fig. 2, is a longitudinal view in cross-section on line 2—2 of Fig. 1; and

Fig. 3, is a transverse cross-section approximately on line 3—3 of Fig. 1.

The casing of the machine may be of any

suitable construction and comprises the side 55 walls 1 and 2, the front wall 3, back 4, top plate 5 and bottom 6. The front, bottom and side walls may be formed in one piece or section which fits against the back and top of the casing and is locked thereto 60 by any suitable means, such as a lock L.

Within the casing is mounted the magazine M for containing the column of goods G. One of the side walls of the magazine is provided with offset portions 6 and 7, 65 the purpose of which will be presently explained. The column of goods rest normally on a tray or shelf 8 which is pivoted on the rod 9 mounted in the side walls of the magazine M. On the rod 9 is mounted a sleeve member 10 which carries the dog 11. A spring 12 coiled on the rod 9 bears at one end against the dog 11 and normally tends to press the same forwardly 70 against the column of goods. The purpose of the dog 11 is to temporarily support the column of goods during the ejecting operation, as more fully explained in my co-pending application, Serial No. 27,302, filed May 11, 1915. 80

On the lug 13, which may conveniently be fixed to one of the side walls of the magazine M, is mounted a hand-operated lever 14 by means of a pivot pin or stud 15. The lever 14 carries a pin 16 on which is mounted the coin-actuated pawl 17. At its upper end the pawl 17 is provided with a hook 18 which normally rests over the shoulder 19 formed in one of the side walls of the magazine-section M. The pawl 17 is provided with a weighted portion 20 which normally holds the hook 18 over the fixed shoulder 19, thereby normally locking the lever 14 90 against operation. 95

On the inner side wall of the magazine-section M is mounted the slide 21 by means of lugs 22 which engage in the slots 23 formed in the slide. The coin-actuated pawl 17 is at its lower end provided with a toe 100 or projection 24 which is adapted to move into the recess 25 formed in the slide 21, when the pawl is actuated by the weight of the deposited coin, as will be presently explained. The recess 25 is formed by the 105 projections 26 and 27 on the slide 21. When the pawl 16 hangs in normal position, the toe 24 is out of alignment with the slide

21 and there is thus no connection between the pawl and the slide.

- The slide 21 is operatively connected to the tilttable delivery shelf 8 through any suitable connection, such as the link 28 which is at its lower end pivoted to the slide (as indicated by the dotted lines 29 in Fig. 1), and at its upper end pivoted to the shelf 8. The result of this connection is that when the slide 21 is pulled downwardly, the shelf 9 is rocked forwardly to allow the bottom piece of goods to drop out of the magazine. As this construction forms no part of the invention claimed in this case, and is moreover described in detail in my aforesaid co-pending application, Serial No. 27,302, I do not deem it necessary to describe with more detail the operation and construction of the delivery mechanism which causes the goods to be ejected out of the magazine. I will but add that when the hand-operated lever 14 is tilted down, the bracket 30 carried by the lever moves out of engagement with the dog 11 and thus allows the spring 12 to press the upper end of the dog against the article next to be delivered, thereby sustaining the entire column of articles during the delivery operation.
- The casing is provided with a suitable coin-chute S which is in alinement with the coin-entrance opening 31 formed in the top of the casing. The coin-chute S is supported in position by any suitable means, such as the brackets 32 and 33 secured to the front wall of the casing. As shown in Fig. 1, one corner of the lower portion of the coin-chute is cut away to accommodate the extension 34 of the pawl 17. This extension 34 is provided with a lateral shoulder 35 which co-operates with the opposite end wall of the coin-chute to temporarily support the deposited coin, which is indicated by the dotted lines C in Fig. 1.
- The operation of the coin-actuated pawl 17 will now be clearly understood and is as follows:
- As previously stated, normally the pawl 17 hangs in a position in which the hook 18 is over the fixed shoulder 19, so that the pawl is locked against downward movement. However, when a proper coin is deposited, the weight of the coin rocks the pawl into a position to bring the toe 24 into the recess 25 of the slide 21, whereby the toe 24 is just above the projection 27 of the slide. The movement of the pawl 17 under the weight of the coin also moves the hook 18 away from the shoulder 19, thereby unlocking the lever 14 for operation. When now the lever 14 is pressed downwardly by means of suitable connections, which will be presently described, the toe portion 24 engages the projection 27 of the slide 21 and forces the latter downwardly. This downward

movement of the slide 21 rocks the delivery shelf 8 which releases the lowermost article for delivery to the bottom of the casing whence it is removed by the purchaser.

The lever 14 is operated from the outside 70 of the casing by means of a knob or button 36 which is connected to the slide 37 through a vertical slot provided in the side wall 1 of the casing. The slide 37 is provided with a pair of spaced projections 38 between 75 which extends the free end of the lever 14. A suitable spring 39, connected at its upper end to the casing and at its lower end to the slide 37, normally holds the latter in uppermost position and thereby also holds 80 the lever 14 in the position shown in Fig. 1. Upon release of the button 36 after operation of the machine, the spring 39 automatically returns the parts to normal position.

The above described mechanisms do not 85 in and of themselves form any part of my present invention, for they are set forth and claimed in my aforesaid co-pending application, Serial No. 27,302, and in my co-pending divisional application, Serial No. 90 58,542, filed October 29, 1915.

I will now describe the slot-closing mechanism which forms the subject-matter of my present application.

Beneath the top 5 of the casing is mounted 95 a pair of spring-pressed levers 40 and 41. The lever 40 is pivoted on the stud 42, while the lever 41 is pivoted on the stud 43. The studs 42 and 43 are carried by a suitable bracket 44 which is fixed to the underside 100 of the top 5 of the casing. The lever 40 may properly be called the washer-catching member, and the lever 41 the controlling member. The lever 41 also constitutes the obstructing member, for it has a portion 45 105 which normally extends across one end of the coin-entrance slot 31, as clearly shown in Fig. 3. A suitable coiled spring 46 normally tends to throw the lever 40 across the coin-slot 31. However, a stronger spring 110 47 normally holds the lever 41 in position to withhold the free end 48 of the lever 40 out of the coin-slot 31. The precise form or arrangement of the levers 40 and 41 is immaterial. In the specific form shown in 115 the drawings, the lever 41 is provided with an extension 49 which engages the extension 50 formed on the lever 40.

The operation of the levers 40 and 41 will be clearly understood from the foregoing 120 and may be stated as follows:

When a proper coin is deposited, it engages the obstructing portion 45 of the lever 41 and rocks the lever against the tension of spring 47. This rocking of the lever 41 moves the extension 49 out of engagement with the washer-catching lever 40, and the spring 46 thereby tends to throw the free end 48 of the lever 40 into the coin-slot against the coin. However, as 130

the spring 46 is weak, the frictional engagement between the end 48 of the lever 40 and the coin is but slight and there is no difficulty whatever in forcing the coin past the levers 40 and 41 into the coin-chute which guides it into its operative position. However, when a washer is thrust into the coin-entrance slot, the spring 46 forces the free end 48 of the lever 40 through the opening 10 in the washer as soon as that opening comes into alignment with the end 48. In this way the washer is positively locked against further insertion into the coin-slot. The lower edge of the end 48 of the lever 40 is 15 beveled so that the washer may be readily withdrawn.

The washer-catching mechanism above described does not in and of itself constitute a part of my present invention, because it 20 forms the subject-matter of my co-pending application, Serial No. 781,072, filed July 25, 1913. The present invention consists in combining with the aforesaid washer catching device (or, more broadly speaking, with 25 the obstructing member 41) means for automatically locking the member 41 in obstructing position when the supply of goods becomes exhausted. In the broad aspect of my invention, this means is not limited to any 30 particular form or arrangement of mechanism. In the accompanying drawings, I show what I consider to be a preferred form of mechanism for controlling the obstructing member 41 to lock the same when the magazine is empty.

On the column of goods G rests a suitable weight W on which is slidably mounted a plate 51 by means of lugs 52 which engage in slots 53 of the slide. The front wall or 40 flange 54 of the magazine-section M is formed with a cam portion 55. The slide 51 is provided with a forwardly extending projection 56 which is adapted to engage the cam portion 55 and thereby force the extension 57 of 45 the slide 51 out of the magazine through the slot 58 formed by the offset portion 7. On the inner side wall of the magazine-section is slidably mounted the bar 59 by means of 50 lugs 60 which engage slots 61 in the bar. The bar 59 rests by gravity in the position 55 shown in Fig. 2. An arm 62 is pivoted at 63 to the inner side wall of the magazine-section M. The forward end of this arm engages the lower end of the vertical slide bar 59, while the rear end of the arm 62 is in alignment 60 with the extension 57 of the slide 51, and is adapted to be engaged by said extension when the slide has been shifted to its extreme position by the coöperation of the lug 56 and the cam portion 55.

When the bar 59 is in normal position, the upper end 59^a thereof is below the lever 41. However, when the bar 59 is lifted to its uppermost position, the end 59^a stands in the 65 path of movement of the lever 41 and posi-

tively locks the same against movement by a coin attempted to be inserted into the machine. It should be remembered that the portion 45 of the lever 41 is always in obstructing position and permits the insertion 70 of a coin into the machine only when the lever 41 is free to be rocked. Consequently, when the bar 59 locks the lever 41 against operation, the coin cannot be inserted into the machine.

The manner in which the bar 59 is lifted into locking position when the magazine is empty, will be clearly understood from the foregoing description, and may be briefly described as follows:

After the weight W in the magazine has descended a sufficient distance, the shoulder 56 of the slide 51 comes into contact with the cam portion 55 and the slide is thereby gradually forced to the left (as viewed in Fig. 1), 85 until the extension 57 of the slide is in alignment with the arm 62. This occurs when all but one piece of goods have been delivered from the machine. Now, after the last piece has been ejected and the parts are returning 90 to normal position, the weight G drops on to the delivery-shelf 8. When this occurs, the extension 57 on the slide 51 strikes the rear end of the arm 62 and thereby throws the bar 95 59 upwardly into locking position, thereby closing the coin-entrance slot 31, as above explained. The bar 59 remains in its locking position as long as the magazine is empty.

To facilitate the insertion of the weight W into the magazine, I provide the slide 51 100 with a finger piece 64 by means of which the weight on the slide may be lowered into the magazine or removed therefrom. The offset portion 6 of the magazine-section M permits the weight to be inserted no matter in what 105 position the slide 51 is, for the offset portion 6 will guide the slide 51 into the magazine even should the slide be in shifted position.

It will be clear from the foregoing that I have provided an exceedingly simple and efficient mechanism for automatically closing the coin-entrance slot of a vending machine when the magazine is empty.

Although I have above set forth a slot-closing mechanism of certain specific construction, I would have it understood that I have shown and described this specific construction merely for the sake of illustration, and that in the broad aspect of my invention the principle thereof may be mechanically carried out in other ways than that herein set forth, without departing from the scope of the invention as defined in the appended claims.

Having thus described my invention what 125 I claim as new and desire to secure by Letters Patent of the United States, is:

1. In a coin-controlled vending machine, a casing provided with a coin-slot, a magazine for containing the vendible goods,

mechanism controlled by the deposited coin for causing delivery of said goods, a yieldable member normally obstructing said coin-slot, a weight or follower for the goods in said magazine, a slide movably mounted on said weight and adapted to be automatically shifted when the supply of goods becomes exhausted, and means whereby the shifted slide locks said member in normal or obstructing position.

2. In a coin-controlled vending machine, a casing provided with a coin-slot, a magazine for containing the vendible goods, mechanism controlled by the deposited coin for causing delivery of said goods, a yieldable member normally obstructing said coin-slot, a weight or follower for the goods in said magazine, and movable means between said weight and said member for automatically locking said member in normal or obstructing position when the supply of goods in said magazine becomes exhausted.

3. In a coin-controlled vending machine, a casing provided with a coin-slot, a magazine for containing the vendible goods, a weight or follower for the goods in said magazine, a member movably mounted on said weight, and mechanism controlled by said member for automatically obstructing said coin-slot when the supply of goods in said magazine becomes exhausted.

4. In a coin-controlled vending machine, a casing provided with a coin-slot, a magazine for containing the vendible goods, a weight or follower for the goods in said magazine, a member movably mounted on said weight, a vertical reciprocable bar adapted to be actuated by said member when the supply of goods becomes exhausted, and a slot-closing device controlled by said bar.

5. In a coin-controlled vending machine, a casing provided with a coin-slot, a magazine for containing the vendible goods, a weight or follower for the goods in said magazine, a slide movably mounted on said weight, means for automatically shifting said slide when the supply of goods becomes exhausted, and mechanism controlled by the

shifted slide for automatically obstructing 50 said coin-slot.

6. In a coin-controlled vending machine, a casing provided with a coin-slot, a device arranged at said coin-slot and having a yieldable portion adapted to be engaged by 55 the inserted coin, a magazine for containing the vendible goods, a weight or follower for the goods in said magazine, a slide mounted on said weight, and means controlled by said slide for automatically locking 60 yieldable portion against movement when the supply of goods in the magazine becomes exhausted.

7. In a coin-controlled vending machine, a casing provided with a coin-entrance slot, 65 a vertical magazine for containing the vendible goods, a vertically slidable bar mounted at one side of said magazine and normally in a lowermost position, a descending weight or follower in said magazine on 70 top of the column of goods, an operating member for said bar, means for actuating said member when said weight reaches the bottom of said magazine to raise said bar, and means for locking said slot against the 75 entrance of a coin when said bar is in raised position.

8. In a coin-controlled vending machine, a substantially rectangular casing having a coin-entrance slot in its top, a spring-pressed 80 pivoted member mounted beneath said top and yieldably obstructing said coin-slot, a vertically reciprocable bar adapted when raised to lock said member in obstructing position, said bar being normally in a position to permit movement of said member by the entering coin, a magazine for containing the vendible goods, a weight in said magazine, and means whereby said weight automatically raises said bar when the goods 85 in the magazine are exhausted.

In witness whereof I hereunto subscribe my name this 26th day of October, 1915.

ALBERT D. GROVER.
